UNITED STATES PATENT OFFICE.

CHARLES BUEK, OF NEW YORK, N. Y., ASSIGNOR TO G. W. RADER & CO., OF SAME PLACE.

CHIMNEY-FLUE.

SPECIFICATION forming part of Letters Patent No. 268,770, dated December 5, 1882.

Application filed September 22, 1882. (No model.)

To all whom it may concern:

Be it known that I, CHARLES BUEK, of the city, county, and State of New York, have invented certain new and useful Improvements 5 in Chimney-Flues, of which the following is a specification.

This invention has reference to an improved chimney-flue, which, when set into the wall, forms with the same intermediate air-spaces, by which the wall is prevented from getting hot; and the invention consists of a chimney-flue provided with exterior longitudinal ribs.

In the accompanying drawings, Figures 1 15 and 2 represent a perspective view of my improved chimney or ventilating flue.

Similar letters of reference indicate corresponding parts.

A represents the body of my improved 20 chimney-flue, which is either made of square or cylindrical shape, or preferably with straight or flattened sides and rounded-off ends. The flue A is provided with exterior longitudinal ribs, a, against which the bricks of the wall are laid, so that the wall is kept away from the 25 body of the flue, whereby air-spaces are formed

between the wall and flue, that prevent the wall from getting hot, and that induce also, by the heating of the chimney, an active ventilation in the longitudinal air-spaces. When 30 the flue is used for ventilating purposes it is preferably supplied at one end with a socket or sleeve, b, as shown in Fig. 2, said sleeve extending only around the ends, but not around the sides, whereby longitudinal air-spaces are 35 formed at both sides of the flue, and a ventilating action at the inside and outside of the flue obtained.

Having thus described my invention, I claim as new and desire to secure by Letters Patent— 40

A chimney or ventilating flue provided with exterior longitudinal ribs, whereby ventilating air-spaces are formed between the wall and flue, substantially as set forth.

In testimony that I claim the foregoing as 45 my invention I have signed my name in presence of two subscribing witnesses.

CHAS. BUEK.
